UNITED STATES PATENT OFFICE

2,445,493

VALVE ACTUATING MEANS

Vall C. Priest, Mountainair, N. Mex.

Application July 9, 1946, Serial No. 682,321

1 Claim. (Cl. 74—569)

1

This invention relates to new and useful improvements and structural refinements in valve actuating means, more specifically, in means for actuating valves, particularly overhead valves, in internal combustion engines of automobiles and similar vehicles.

The principal object of the invention is to provide valve actuating means in which the valve clearance gap is formed within the body of the valve tappet, rather than between the push rod and the rocker arm.

A further object of the invention is to provide valve actuating means wherein the component parts between which the clearance gap is formed are constantly bathed in oil, thereby preventing what is commonly referred to as the tappet noise.

An additional object of the invention is to provide valve actuating means which does not, in any way, interfere with the normal operation and function of the valve.

A still further object of the invention is to provide valve actuating means which are simple in construction and which can be readily manufactured.

With the above and more important objects in view and such other objects as may become apparent as this specification proceeds, the invention consists essentially of the construction and arrangement of parts as shown in the accompanying drawings in which:

Figure 1 is a cross-sectional view of the invention.

Figure 2 is a top plan view of the tappet per se.

Figure 3 is a cross-sectional view taken substantially in the plane of the line 3—3 in Figure 2.

Figure 4 is a cross-sectional view taken substantially in the plane of the line 4—4 in Figure 3, and

Figure 5 is a perspective view of a plunger used in the invention.

Like characters of reference are used to designate like parts in the specification and throughout the several views.

Referring now to the accompanying drawings in detail, the invention embodies in its construction a valve tappet, designated generally by the reference character 10, the same being reciprocated as a whole within the valve tappet guide 11 provided in the engine block.

The tappet 10 consists of a cylindrical sleeve 12 which constitutes the follower of a cam 13, the sleeve 12 enclosing a cylinder 14 provided with an axially extending bore 15 and closed at the lower end thereof by a base plug 16.

The upper end of the cylinder 14 is formed with

2

an inturned shoulder 17 and is beveled substantially as shown at 18. The shouldered portion of the cylinder 14 is formed with a plurality of longitudinally extending oil passages 19, the same being inwardly convergent and the purpose thereof being hereinafter more fully explained.

A plunger 20 is slidably positioned in the bore 15 of the cylinder 14, this plunger being substantially cylindrical in configuration and being provided with further, longitudinally extending oil passages 21. The passages 21 are formed adjacent the lateral edge of the plunger and the latter is formed at each end thereof with substantially cylindrical abutments 22, 23, as is best shown in the accompanying Figure 5.

The abutments 22, 23 are of relatively smaller diameter with respect to the main body portion of the plunger and the upper of the abutments (22) is formed with a concave depression 24 forming a seat for the push rod 25.

This push rod is of conventional design and the upper end thereof engages through the medium of a ball and socket joint 26 one end of a rocker arm 27, which in turn is pivoted as at 28, while its remaining end actuates the valve 29.

The aforementioned plug 16 is provided with a further abutment 30, which coacts with the aforementioned abutment 23 to form the clearance gap 31. A suitable compression spring 32 is interposed between the plunger 20 and the plug 16, as will be clearly apparent in the accompanying drawings.

When the invention is placed in use, the spring 32 will normally urge the plunger 20 against the inner face of the shoulder 17, thus facilitating maintenance of the gap 31 and permitting expansion of the push rod 25, etc., under heat. As the cam 13 forces the tappet 10 upwardly, the adjacent surfaces of the abutments 23 and 30 will be brought into contact and resultingly, the valve 29 will be actuated in the conventional manner.

It will be noted that the oil passages 19 and 21 will facilitate free flow of oil from the bore 15 to the push rod seat 24, thereby assuring noiseless operation of the tappet.

It is believed that the advantages and use of the invention will be clearly understood from the foregoing disclosure and accordingly, further description thereof at this point is considered unnecessary.

While in the foregoing there has been shown and described the preferred embodiment of this invention it is to be understood that minor changes in the details of construction, combina-

tion and arrangement of parts may be resorted to without departing from the spirit and scope of the invention as claimed.

What I claim as my invention is:

Valve actuating means comprising in combination, a cam actuated cylinder and a base plug in the lower end thereof, an inturned shoulder at the upper end of said cylinder, a plunger slidably positioned in said cylinder and forming a push rod seat, coaxing abutments on the adjacent surfaces of said plunger and said plug, a compression spring between said plunger and said plug, the adjacent surfaces of said abutments being nor-

mally spaced and forming a clearance gap, and a plurality of oil passages provided in said plunger and in said shoulder.

VALL C. PRIEST.
